R. A. DUPONT

RESERVE THREAD MECHANISM FOR SELF ACTING SPINNING MULES

Filed April 18, 1924

Inventor
René Abel Dupont.
By Henry C. F. atty.

UNITED STATES PATENT OFFICE.

RENÉ ABEL DUPONT, OF GLAGEON-NORD, FRANCE.

RESERVE-THREAD MECHANISM FOR SELF-ACTING SPINNING MULES.

Application filed April 18, 1924, Serial No. 707,455, and in France April 23, 1923.

My invention relates to an improved reserve thread mechanism for self-acting spinning mules, the purpose of which is to maintain the strictly necessary length of reserve thread unwound on each cop of the mule, when the carriage reaches the end of its inward run.

The present invention refers to improvements which essentially concern the arrangement of the ratchet mounted on the rocking lever and causing, by a suitable transmission device, the rotation of the screw of the quadrant of the mule, so as to lower the nut to which is attached the chain of the barrel on the carriage, and in this manner, reduce the available thread to its normal length. It has also for its object the suppression of the large operating lever and its replacement by an extension of the oscillating beam, the free end of which carries a roller. My invention comprises also various other details of construction of the apparatus which will be described hereafter.

Referring to the annexed drawings:—

Fig. 1 is a general view of the rocking beam carrying the operating lever.

Fig. 2 is a front view of the operating lever.

Figs. 3 to 7 are detail views.

Fig. 8 shows a variation in the operation of the ratchet wheel.

My invention relates to an improvement on the structure shown in my Patent, No. 1,200,820, of October 10, 1916, and like the structure therein aims to have neither too much nor too little reserve thread between the cops and the drawing rolls owing to the cop spindles having made too few turns at the beginning of the cop when its diameter is small, to wind up the fixed length of thread drawn out by the carriage in its outward run; or owing to the cops when they are nearly full, tending to consume more thread than has been drawn out by the carriage. The cop spindles rotate a constant speed independent of the diameter of the cop and in my cited patent I have invented certain mechanism for automatically regulating the amount of this reserve thread employing a curved lever 29' and mechanism

employing a hinge 92 operated by a screw 93' which had to be turned by the operator to open or close the hinge in accordance with the amount of thread being wound on the cops.

By my present invention I avoid the use of a hinge by changing certain of the structure shown in the patent and make the mule entirely automatic in its control of the reserve thread.

As is seen in Fig. 1, the beam 22 rocks on an axis 22^a at one end and it is provided, on the opposite end, with a counter weight 136. It is enlarged forward of the axis 22^a and the upper portion of this enlargement carries a pawl 24, while, upon its lower portion, is hinged the rod 23, connected at its other end to the rocking beam 20, which is the beam that is engaged by the roller of the counterfaller arm so as to act at the required moment upon the beam 22 to cause a take up of the excess reserve thread.

In order to facilitate the falling back of the beam 22 to its inoperative position, the pawl 24 carries on one side, a rounded portion 24^a (Fig. 4) intended to climb up the slope 137^a of a member 137 (Figs. 5 and 6) fixed against the bracket of the support 77 (Fig. 1). The purpose of this arrangement is to free the ratchet 24^b from the teeth of the ratchet wheel 25, when the beam 22 falls back to its non operative position, on the one hand under the influence of the roller 29^a of the operative lever 29 meeting the slope 38—39 and on the other hand under the action of the counterweight 136.

The large hook shaped lever 29' in my prior United States Patent No. 1,200,820, is replaced by an extension 29 of the beam 22 (Fig. 1) terminated by the roller 29^a. When there is an excess of reserve thread, that is, when the roller of the counter-faller arm has butted against the curved lever 20, the latter oscillates and, by means of the connecting rod 23 the beam 22 rocks also; the roller 29 comes then into a lowered position proportional to the excess of reserve thread, and into the path of the carriage slope 38, is lifted and in turn, lifts the operating lever 29.

For the purpose of doing away with the clutch sleeve 52 and the counter-clutch sleeve 56 described in the precited patent, I use here a latch 138 (Figs. 1 to 7) hinged at 138^a, 5 which maintains the beam 22 in its resting position by means of a hook 138^b coming into engagement upon a pin 139 fixed to the beam.

On the slope or support 39 is fixed a 10 bracket 140 (Fig. 1), carrying a screw 141 provided with a lock-nut, and which buts against the tail 138^c of the latch, so that it is only when the carriage is near the cops that the beam and lever can oscillate.

15 The support 39 carrying the roller 38 described in my prior Patent No. 1,200,820, whose function was to raise the hook shaped lever 29 and 29' have been replaced by the support 39 with the sloping member 38 cast 20 integrally.

The support 39 is fixed to a bracket 40 extending from the carriage and therefore moves with the latter during its inward and outward runs. It also carries the pin 132 of 25 the circular ratchet 131 and the pin 103 of the compensating lever 102.

The hook shaped lever 29 which is shown in my prior Patent No. 1,200,820, as pivoted on pin 37 extending from the support 126, 30 has been eliminated in this device by placing the rocking beam 22 on the support 77.

In the alternative arrangement of the ratchet wheel and of its ratchet shown in Fig. 8, the ratchet wheel 25 and the ratchet 35 24 are mounted on the support 61, which allows the replacement of the upper horizontal chain of the said prior patent by a connecting rod 142 between a crank 143, which replaces the wheel 25, of said patent, 40 and a rocking lever 144, which replaces the pinion 58 and carries the ratchet 24.

When the carriage ends its inward run with too much reserve thread, it is due to the fact that the counterfaller is too high 45 in approaching the cylinders. This counterfaller 1 is carried by the guides 2 fixed on the rod 3 upon which is also mounted a lever 91 carrying at its extremity the roller 19.

When the reserve is normal the roller 50 19 moves below the beam 20 but when there is an excess of reserve thread the counterfaller 1 being then too high, the roller 19 attached thereto encounters the part 20' of the beam or curved lever 20. The latter, 55 through connecting rod 23 and connection 150 pivoted at 151 to the beam 22, tips the big lever 29, 22 to the positions shown in dotted lines at 29^a and 29^b. At this time, the roller 29^a is in a downward position, 60 having moved a distance proportional to the excess of reserve thread. While the big lever 29 is tipping downwardly, the pawl 24 rides over the teeth of the ratchet 25, the latter being located against the beam 22 or

on the support 61. When the carriage next 65 moves on its outward run, the slopes 38, 39, encounters the roller 29^a, causing it to move upwardly and forces the beam 22 to assume its first position. During this movement the pawl 24 causes rotation of the ratchet 25. 70

As has been explained in my Patent No. 1,200,820, this rotation of ratchet wheel 25 is amplified through suitable gearing and is transmitted by means of chains 44 and 45 to the screw 9 of the quadrant 6 of the mule. 75 With the ratchet 25 depending from the axis 59 and mounted in a housing piece 60 carried by 61, it is only necessary to use the vertical chain 45 shown in Fig. 8. The cam member 137 mounted against the support 77 80 near the rocking beam, operates to free the pawl 24 from the ratchet teeth 25 when the beam 22 has fallen back to its position of rest and is then locked in place by means of the latch 138^b which places itself above 85 the axis 139 on the beam 22. Two results follow when the pawl is freed from the ratchet, the fall of the beam 22 is facilitated and downward movement of the lever 29, 90 after passing beyond 38, is avoided.

The lever 29' is articulated so that it may be folded on itself if for any reason it should be lowered while the carriage is on its outward run. For this purpose the arm 145 is attached to the beam 22 and carries an 95 extension 146. The articulation is shown at 147, 148 the parts of the lever being held together by means of the pin 149. It will be seen that should the roller 29' be lower than its position of rest when the carriage makes 100 its inward run, the piece 140 would encounter it and would force it to assume its normal position by severing the pin 149.

I claim:—

1. A reserve thread mechanism for self 105 acting spinning mules comprising: a carriage, a weighted beam, a pawl carried by said beam, an operating lever extending the said weighted beam, a roller carried by the said operating lever, and a sloping element 110 on the carriage to actuate the lever at the required moment.

2. A reserve thread mechanism for self- 115 acting spinning mules comprising: a carriage, a weighted beam, a pawl carried by the said beam, a fixed slope, a rounded portion on the pawl intended to climb upon the fixed slope to free the pawl, an operating lever extending the said weighted beam, and a sloping element on the carriage to actuate 120 the roller at the required moment.

3. A reserve thread mechanism for self 125 acting spinning mules, comprising a carriage with an abutment screw, a weighted beam, a rocking latch with a hook upon which buts the screw of the carriage to maintain the beam in its position of rest, a pawl carried by the said beam, an operating lever

extending the said weighted beam, and a sloping element on the carriage to actuate the roller at the required moment.

4. In a reserve thread mechanism for self-acting spinning mules, the combination with a frame of a weighted beam, a crank with oscillating motion operated by the said beam, a pawl carried by an oscillating lever,

a ratchet wheel engaged with the said pawl the axis of which is mounted in a support 10 in the front of the frame, and a connecting rod connected to the crank and to the oscillating lever of the ratchet.

In testimony that I claim the foregoing as my invention, I have signed by name.

RENÉ ABEL DUPONT.
